ELECTRONIC TUBE SOCKET, HERMETICALLY SEALED

Charles N. Keller, Dayton, Ohio

Application August 28, 1945, Serial No. 613,199

2 Claims. (Cl. 173—328)

(Granted under the act of March 3, 1883, as amended April 30, 1928; 370 O. G. 757)

1

The invention described herein may be manufactured and used by or for the Government for governmental purposes, without the payment to me of any royalty thereon.

The invention to be hereinafter described relates to hermetically sealed tube sockets or connectors.

Where the pin and prong or split tube type is used employing a plurality of cooperating members all or a large number of them being simultaneously coupled by the usual plug-in action, there is always the possibility that one or more of the elements may be slightly out of the necessary positions or locations for proper, adequate and complete connections. Where that is the case, the actions of plugging in, due to such misalignment compels an adjustment or adaptation of one or the other of said cooperating elements. It has been common practice to rigidly anchor the pins and the prongs or split tubes in their respective bases, supports, foundations or other parts by which they are carried and handled. At the present time it is common practice to mount the pins in a glass base or similar part. When this member is plugged in, the cooperating prongs or split tubes being unyieldingly mounted in their base, all improperly placed pins will be forced toward proper positions. This frequently causes cracking of glass base carrying the pins, with obvious destruction of the pin member of the respective element.

The main objects of the present inventions are to avoid the above and other objections and provide a simple, very compact, efficient, sturdy or durable, hermetically sealed tube socket or connector construction and assembly of minimum dimensions and size and capable of quantity productions at relatively low cost.

In order to more clearly disclose the construction, operation and use of the invention, reference should be had to the accompanying drawings forming part of the present application.

Throughout the several figures of the drawings, like reference characters designate the name parts in the different views.

In the drawings:

Fig. 1 is a perspective view of the base and assembled prongs of the preferred form of the invention;

Fig. 2 is a cross section on line 2—2 of Fig 1 with inclosing shell;

Fig. 3 is a view similar to Fig. 2, showing a modification;

Fig. 4 is a fragmentary detail showing a further

2

modification of the connection between a chassis or the like and the invention;

Fig. 5 is an enlarged fragmentary detail indicating relative pin and prong or split tube position, immediately prior to assembly; and

Fig. 6 is a top plan view of the preferred form, assembled, on about the same scale of Fig. 1.

The several views of the drawings show the invention greatly enlarged as a matter of clearness in setting forth the smaller details. As a further means of clearness in showing, only one insert contact prong or split tube and associated parts and construction has been shown in the drawings, as all others are duplicates thereof.

15 The drawings indicate eight, as will be evident from Fig. 1. It will be understood, however, that the number is entirely immaterial to the invention, any desired number being thoroughly permissible.

20 In the present invention a tube socket body or base 1 of glass or a ceramic material provides a mount or support for a plurality of prong members which are flexibly anchored, as will hereinafter be set forth in more detail. This body or base is provided with a plurality of axially extending, radially disposed, chambers

25 2. These chambers, opening through one face of base 1 extend through it to within a short distance of the opposite face. Aligned with, 30 communicating with, and extending through the remaining portions of base 1 is an opening or passage 3. Each chamber 2 is proportioned to loosely completely receive a split tube prong or socket member 4 of usual and well known construction. Chambers 2 are of substantially the same length as the split tubes 4, or slightly longer, of substantially greater lateral cross section and may be of any desired lateral cross

35 sectional outline such as square, circular, elliptical, etc., capable of adequately receiving and accommodating the respective members 4 with due allowance for the desired movement and flexibility of the member in such respective chambers. As usual, each prong member is 40 provided with a contact member 5 of usual and well known construction, either integrally formed with the split tube or suitably secured thereto. In the usual and well known construction and arrangement, the part 5 is in approximate 45 alignment with the split tube 4. It will be clear that, with such disposition of the parts, there would be no construction acting to retain the split tubes 4 in their respective chambers 2.

50 In order to retain split tubes 4 in their respective chambers 2 their contact strips 5, after

55

alignment with the split tube 4. It will be clear that, with such disposition of the parts, there would be no construction acting to retain the split tubes 4 in their respective chambers 2.

In order to retain split tubes 4 in their respective chambers 2 their contact strips 5, after

being passed through the passages 8 are abruptly offset at approximate right angles to provide a base engaging, holding or locking branch or arm 6. In assembling a prong member and its contact terminal in base 1, the offset 6 extends radially outwardly from the outer wall of the respective chamber. Accordingly, the end portion 7 of contact terminal, which part is parallel with the member 4, is radially beyond and out of line relatively to the respective chamber 2. As a result, the offset 6 engages the adjacent face or wall of base 1 and constitutes a stop, preventing withdrawal of member 4, outwardly through its chamber 2. Thus, the contact terminal 5-6-7 extends tortuously through base 1, between it and shell 8 and out through shell 8.

Cooperating with the chambered base or body 1 is a shell 8 which, in the preferred arrangement, is cup-shaped or approximately U-shaped in lateral cross section. This shell is of the same general type of material as that of the base or body 1. In assembled relation, it will be noticed, the shell and base are not closely nested. They do not contact. They are spaced apart by a plurality of barrier and spacing ribs 9. Those same ribs also perform an additional and wholly different function, as will hereinafter more fully appear. Since the shell, in operative position, receives and encloses base or body 1 and its related parts, provision must be made for extension therethrough of the end portions 7 of the contact members 5. For this purpose, the base of shell 8 is provided with a plurality of passages or openings 10 corresponding in number to the number of chambers 2 in 1 and so shaped and disposed as to freely receive and pass the ends 7 of members 5 in such manner that they will project therebeyond for the usual connections. Since the openings 10 are disposed to receive the ends 7 which are radially beyond chambers 2, those passages will also be beyond and out of alignment with chambers 2. With the shell disposed relatively close to base 1, though slightly spaced, each offset 6 will provide considerable flexibility. In order to securely anchor the member 4 and its terminal contact 5-6-7 against movement relative to shell 8, the contact end 7 where it passes out of 10 is securely anchored in 8 by solder 11. Preferably, shallow countersinks, wells, or pockets are formed concentric with the outer ends of 7 to receive the solder. By using any one of a number of well known solders a hermetic seal may be provided against dirt, dust, moisture and conditions of high altitude.

The difficulties of glass-to-glass, metal-to-glass and similar soldering connections, have been overcome by well known practices in which the respective surfaces are first metal coated. Since such steps are no part of the present invention and are well known to those skilled in the art to which this invention relates more detailed description is not advisable in this application.

While a single, simple right angle, offset or bend 6 has been illustrated and described, it is to be understood that a very wide range of bends or offsets may be used and that any bend or offset which will provide the desired flexibility of connection between the tubular prong member and shell 8 is considered as falling within the field of the present invention. Such flexibility permits approximately universal movement of split tube 4 relatively to the anchored part of 1 in the shell so that they may make any adjusting movement. In addition to the several chambers 2 base 1 may be provided with a centrally disposed and

5 axially extending opening 12 with countersink 13 for solder 16 for anchoring 16 in 8. Removably locked in 12 in usual manner is the central grounding tube socket 14 provided with spurs 15 adapted to snap over and engage the face of the countersink 13. As usual, it is provided with a terminal contact 16 which extends through a passage through 8 and is hermetically sealed therein by solder, as in the case of terminal contact strips 5. The usual tube may be seated in that central socket in well known manner.

10 From the above, it will be noted that base 1 and shell 8 are connected by the contact terminals only. Due to the flexibility imparted by the offsets and the further fact that the only connection is a surface engagement and not a fixed fastening connection, there is no rigidity of the split metal tubular prong member. Consequently, as the pins 17 are inserted in the members 4 those members are free to move and do move to adjust themselves to any inaccuracies in the mounting or spacing of the pins. As a result of this, the pins will not be forced from their fixed positions and their glass base or mount will not be cracked and destroyed. Nor will the members 4 or their mounting be damaged as in the case where members 4 are permanently fixed in their positions and can not yield. Nor is there any danger of injuring or destroying any of the various hermetic seals where the terminals pass through the shell 8.

15 To complete the hermetic seal assembly, an attaching flange 18 may be secured to the lower outer circumferential wall of the shell 8 and that, in turn, may be suitably secured in any well known manner to the chassis of any desired piece of equipment. In the modification of Fig. 3 a plate 19 is substituted for the shell 8, the two being hermetically sealed circumferentially along the adjacent edges, as at 20. In this form, a somewhat different type of attaching flange is used.

20 While the construction of Fig. 2 is the preferred construction, the connection there shown between the shell and a chassis may be simplified in accordance with the showing of Fig. 4. In Fig. 4 it will be noticed that the shell 8 is formed with a circumferential, radially outwardly extending or annular shoulder 21. This shoulder may be hermetically sealed direct to the adjacent edge of the chassis or other part, without any intervening connecting flange. Various other connections between the base or body 1 or cup 8 and a chassis or equivalent member may, obviously, be used. From the above it will be clear that the 25 unit containing the prong members is thoroughly hermetically sealed at every point where sealing is necessary, including the points of outlet for the contact terminals and the connections between that unit and an equipment chassis or other part with which the unit is to be connected.

30 Reference was made earlier to barriers and spacing ribs 9. These ribs, in addition to spacing the shell and base, as will be clear on reference to Fig. 1, extend between the contact terminals of the successive electrically conductive elements 4. This intervention completely isolates and insulates successive conductors and provides an increased dielectric path between adjacent conductors. As a further assurance, a second set of such barriers 9¹ is provided on the outer face or wall of the shell 8 or plate 19. This second set has, of course, no mechanical spacing function corresponding to that of ribs 9. Its function

is entirely that of electrical isolation and insulation and increased dielectric path.

Glass and ceramic material have been stated as preferred material. It is to be clearly understood that various acceptable plastics as well as any other suitable material may be used.

While the construction illustrated is clearly applicable to radio use, it is also applicable to many other uses. It is thoroughly applicable in all cases in which connection is completed by a plug-in action of a pin member into a cooperating prong, split tube or socket member and in which one or the other of the male and female assembly may be inaccurately disposed, requiring automatic adjustment into properly cooperating positions during the plug-in connection. Likewise it is applicable whether one pin and cooperating prong or many such are involved.

It is thought that the construction, operation and use of the invention will be clear from the preceding detailed description.

Many changes may be made in the construction, arrangement and disposition of various parts of the invention within the scope of the appended claims without departing from the field of the invention and it is meant to include all such within this application wherein only one preferred form with several modifications have been illustrated, purely by way of example, and with no thought or intention to, in any degree, limit the invention thereby.

Having thus described my invention, what I claim and desire to protect by Letters Patent is:

1. A socket assembly comprising a base, a plurality of tubular members resiliently mounted therein, each of said members carrying a contact strip, a shell enclosing said base in spaced relationship thereto, each of said strips extending through said base and shell, the portion of each strip extending through said base being out of register with the portion extending through said shell, the portion of each strip disposed in the space between said base and shell being offset from said other portions, means anchoring said

strips in said shell, dielectric barriers between said base and shell and extending between successive contact strips, and external dielectric barriers carried by said shell and extending between successive contact strips.

2. A socket assembly to receive resiliently the pin members carried by a tube, said socket comprising a base having a plurality of terminal chambers, a shell enclosing one end of said base and in spaced relationship thereto, and a plurality of contact strips, each of said strips having a contact portion and a terminal portion, said contact portion being out of register with said chamber and extending through and external of said shell and affixed thereto, said terminal portion being positioned within said chamber and having a transverse dimension substantially less than the transverse dimension of said chamber whereby said terminal portion may move laterally within said chamber, each of said strips being shaped to form a shoulder between said contact and terminal portions, said shoulder being disposed in the space determined by the spacing between said base and said shell whereby said terminal portion may be laterally and longitudinally displaced to engage flexibly said pin members.
